MULTI-LEVEL AQUARIUM FILTER

Herbert R. Axelrod, Deal, N.J., assignor to T.F.H. Publications, Inc., Jersey City, N.J., a corporation of New Jersey

Filed Nov. 22, 1965, Ser. No. 88,177

Term of patent 14 years

(Cl. D91—1)

FIG. 1

FIG. 2

FIG. 3

FIG. 4

FIG. 5

FIGURE 1 is a perspective view of a multi-level aquarium filter, showing my new design;

FIGURE 2 is a top plan view in reduced scale of said filter;

FIGURE 3 is a rear elevational view of said filter;

FIGURE 4 is a side elevational view of said filter; and

FIGURE 5 is a front elevational view of said filter.

I claim:

The ornamental design for a multi-level aquarium filter, substantially as shown.
